SLEEVE FOR INDIRECTLY HEATED CATHODE HAVING AN INTEGRAL TAB

Robert Friedli, Jr., Irvington, N. J., assignor to
Radio Corporation of America, a corporation
of Delaware

Application November 30, 1948, Serial No. 62,734

8 Claims. (Cl. 313—331)

1

The present invention relates to cathodes for electron discharge devices, and more particularly to a cathode sleeve having an integral tab for connection to a lead-in, and method of making the same.

Cathode sleeves having integral tabs have heretofore been made by stamping a sheet metal stock to provide a planar form of predetermined outline usually taking the shape of a main rectangular body with a tab extending from one edge thereof. The entire form including the tab is then shaped on a mandrel which may be cylindrical, to provide a cylindrical sleeve with a tab extending from one end thereof. The entire length of the tab is also caused to conform to the shape of the mandrel, resulting in a curvature therein in a transverse plane and an alignment of the tab with a longitudinal portion of the sleeve. In some instances, the sleeve is also provided with a bead adjacent the end thereof remote from the tab. The tab is usually longer than the spacing of the bead from the adjacent end of the sleeve.

Several problems are encountered in the handling and ultimate utilization in an electron discharge device of a cathode sleeve having a bead and an integral tab characterized by a transverse curvature throughout its length. For example, modern sleeve making machines are relatively fast in operation and consequently require a means for rapidly removing completed cathode sleeves therefrom. One means found suitable and generally used comprises an elongated mandrel on which the finished sleeves are threaded in tandem and along which they slide to a suitable receptacle. The cathode sleeves are fed to the elongated mandrel in such manner that the beaded end of one sleeve is in butt relation to the tabbed end of an adjacent sleeve. Where the tab is in alignment with the sleeve and has a transverse curvature throughout its length, the tab on one sleeve will engage the bead on the adjacent sleeve prior to butt engagement of adjacent ends of the sleeve proper. Since the transverse curvature of the tab at its free end is the same as that of the sleeve and the bead, the entire free end of the tab will butt against the bead. This results in impedance to further travel of one sleeve with respect to the other on the elongated mandrel and usually causes a buckling or collapse of the tab. Such collapse of the tab necessitates a manual straightening operation which requires a slowing down of the sleeve making machine and tedious and tiring work of one or more operators. The end result of the

2

difficulty occasioned by curved cathode tabs of the prior art is an increase in the cost of electron discharge devices in which integrally tabbed cathode sleeves are employed.

5 While the cause for this buckling or collapse of the tab is understood to reside in the in-line extension of the tab from the sleeve, attempts heretofore made to deflect the tab laterally have proven impractical due to prohibitive costs in adapting a sleeve making machine for this purpose. It has been deemed more economical in prior practices to resort to manual handling of each sleeve as it comes from the machine than to modify existing machines.

10 Another problem arises when a cathode sleeve having a transversely curved tab is connected to its associated lead-in. The operation of connecting a lead-in to the cathode tab usually involves disposing an end portion of the lead-in wire transversely with respect to the tab and fixing the connection as by welding. When the tab is curved transversely throughout its length, the engagement between the lead-in wire and the tab is tangential when the outwardly curved side of the tab is engaged by the lead-in. When the inwardly curved side of the tab is engaged by the lead-in only the longitudinal edges of the tab engage the lead-in. As a consequence of the curvature in the tab therefore, only a relatively small surface engagement is possible between the tab and the lead-in resulting in a relatively weak connection and possible electrical disturbances due to the restricted electrical path provided by such weak connection.

15 20 25 30 35 It is, therefore, the object of the invention to provide an integrally tabbed cathode sleeve capable of delivery from a cathode sleeve making machine at a relatively fast rate and adapted for good connection to a lead-in, and a method for making such sleeve.

40 45 A further object is to provide a cathode having an integral tab at one end and a bead adjacent the other end wherein butt relation between two sleeves is permitted without a collapse of the tab.

50 Another object is to provide a cathode sleeve having a peripheral or annular bead adjacent one end and an integral tab extending from the other end and capable of tandem travel with like sleeves on a mandrel without a collapse of the tab.

55 A further object is to provide a cathode sleeve having an annular bead spaced a predetermined distance from one end thereof and an integral tab at the other end extending therefrom a distance greater than said predetermined distance,

the tab having a structure enabling a butt relation of two sleeves without collapse of the tab.

Another object is to provide an integral tab at one end of a sleeve-type cathode and a bead at the other end thereof spaced from said end by a distance less than the length of said tab, said tab being laterally deflected to clear the end of an adjacent sleeve and capable of further lateral deflection by the bead of an adjacent aligned sleeve to permit butt end engagement of two sleeves without collapse of the tab.

Another object is to provide an integral tab on a cathode sleeve having a surface permitting good connection to a lead-in.

An additional object is to provide an integral tab on a cathode sleeve which has a curvature throughout a portion of its length and which is flat throughout another portion of its length, said last named portion extending to the end of the tab and providing a relatively small contact area at the free end thereof for engaging the bead on an adjacent sleeve for lateral deflection of the tab, while providing a relatively large surface area for accomplishing a good mechanical and electrical connection to a lead-in.

A further object is to provide a relatively simple and economical method for making a cathode sleeve and an integral tab wherein the end portion of the tab is substantially planar and is slightly deflected laterally from an end projection of the sleeve.

Another object is to provide a method for forming an integral cathode tab so as to have a rounded longitudinal portion and a flattened longitudinal portion automatically deflected laterally during the forming step.

Further objects and advantages of the invention will become apparent as the description proceeds.

In the drawing to which reference is now made for a better understanding of the invention, several embodiments of the invention are presented by way of illustration only and not by way of limitation.

Figure 1 shows an electron discharge device partly broken away, incorporating the novel cathode sleeve of the invention;

Figure 2 is a side elevation of my novel cathode sleeve;

Figures 3 and 4 are, respectively, cross sections taken along the line 3-3 and 4-4 of Figure 2 and illustrate the transverse shapes of different longitudinal portions of the integral tab on my novel cathode sleeve;

Figures 5, 6, 7 and 8 illustrate advantages of my cathode sleeve in being capable of rapid removal from a cathode sleeve making machine without collapse of the tab, Figure 5 showing a plurality of my novel sleeves threaded for travel in tandem on a mandrel, Figure 6 showing a stage in the feed of the sleeve in the mandrel in which the tab on one sleeve engages the bead on another sleeve prior to butt engagement of the sleeves; Figure 7 illustrating the cross section of the tab at its point of engagement with the bead and indicating the relatively small surface engagement between the tab and the bead, and Figure 8 showing the substantially larger surface engagement resulting from the use of conventional cathode tabs of rounded cross section throughout their lengths which causes collapse of the tab;

Figures 9, 10 and 11 illustrate my novel method, Figure 9 showing the flat stock from which my novel sleeve and integral tab are formed, Figure 75

10 indicating in cross section a side view of a tool I may employ in carrying out my method, and Figure 11 depicting a transverse section of Figure 10 along the lines 11-11 and further illustrating my novel method; and

Figures 12, 13 and 14 depict advantages of my novel cathode sleeve in connecting it to a lead-in, Figure 12 showing the relatively large surface engagement permitted by my novel cathode tab with a lead-in, and Figures 12 and 14 showing the relatively small surface engagement permitted between the curved tab of the prior art and a lead-in.

Referring now in more detail to the drawing, there is shown in Figure 1 an electron discharge device having an envelope 20, a base 21 having contact prongs 22 and an electrode assembly including anode 23 and cathode 24 having an integral tab 25 connected to a lead-in 26.

According to the invention, and as more clearly shown in Figures 2, 3 and 4, cathode 24 includes a sleeve 27 having an integral tab 25 which in turn has a longitudinal portion 28 curved transversely as shown in Figure 4 to constitute a longitudinal projection of a portion of the end of sleeve 27, and another longitudinal portion 29 adjacent its free end having a transverse section that is substantially rectangular as shown in Figure 3 and slightly deflected laterally of the sleeve 27. The sleeve 27 may also be provided with an annular or peripheral bead 30 adjacent its end remote from the tab 25. The bead 30 is spaced from the adjacent end of sleeve 27 a sufficient distance to permit the adjacent end to protrude a short distance above a spacer plate 31 shown in Figure 1 with the bead bearing against a surface of the plate. In comparison with the spacing of bead 30 from the adjacent end of sleeve 27, the length of tab 25 is relatively large, for the reason that a relatively long tab is required for facilitating connection thereof to a lead-in.

This structure of my novel cathode sleeve and tab is advantageous in several respects. One advantage is indicated in Figures 5, 6 and 7 in connection with an arrangement for rapidly removing the finished sleeves from a sleeve making machine. In this arrangement the sleeves 27 are threaded on a mandrel 32 having a shape conforming to the shape of the space defined by the sleeve. This shape for example may be cylindrical. The sleeves 27 are fed to mandrel 32 from the right-hand side and after traversing the mandrel the sleeves drop from the left-hand end thereof to a suitable receptacle not shown. Motive means, not shown, for causing the sleeves to slide along the mandrel is applied to the sleeve initially placed on the mandrel at its right-hand end after the sleeve has been formed by a machine, not shown. Such machine usually includes an elongated forming die, not shown, on which the sleeve is formed. Mandrel 32 may be placed in end relationship to such forming die for receipt of finished sleeves therefrom. A sleeve initially threaded on mandrel 32 by said motive means is given further movement by a pushing action imparted by a following sleeve. To permit of such pushing action the pushing sleeve and the sleeve being pushed are required to assume an abutting end relationship.

Heretofore this abutting end relationship of the sleeves has resulted in a buckling or collapse of the tab on one of the sleeves on engaging the bead 30 on another sleeve. This is for the reason that such tabs have usually had a curved cross section 33 as shown in Figure 8 which is

usually angularly similar to the transverse curvature of the wall of sleeve 21. This results in a relatively large area of engagement between the end of tab 33 on one sleeve and the end 21 of an adjacent sleeve, which results in the transmission of a relatively large force to the tab 33, as a consequence of which it buckles or collapses.

In accordance with the invention, however, as shown in Figure 7 the flattening of the end portion 29 of the tab 25 and a deflection laterally thereof results in a clearance between the end 29 of the tab and the end of an adjacent sleeve and in addition provides a relatively small surface engagement between the end of tab 25 and the bead 30. This engagement involves such a small surface that the tab responds in further lateral deflection to the pushing action of the pushing sleeve whereby the tab is preserved against buckling or collapse.

Several reasons for this response of my novel tab are evident. When the tab 33 is rounded throughout its length the consequent increase in the area of engagement between the tab end and the bead 30 results in a relatively large magnitude of friction between the two which imparts an undesirable amount of force to the tab. My novel tab having a flat end portion involves less surface engagement and consequently less friction, as shown in Fig. 7. Again, the tab 33 is not easily deflectable laterally because of its curvature, the curvature imparting such a degree of resistance to lateral components of force that the curved tab resists deflection to a considerably greater degree than does the tab of the invention having the flattened end portion 29 as shown in Figure 7. Therefore, my novel tab responds in deflection to a force that is far less than that required to cause it to buckle whereas the rounded tab of the prior art is inherently incapable of lateral deflection without considerable distortion of its shape resulting in buckling.

The initial deflection laterally of my novel tab results automatically from the method I employ in forming the sleeve. This method is illustrated in Figures 9, 10 and 11. My novel sleeve is first stamped from sheet metal stock to form a planar body 36 having a rectangular portion 37 and a tab 38. This planar body is then placed between two parts of a forming tool shown in Figures 10 and 11.

This forming tool includes a mandrel shaped anvil 39 and a pressing member 40. The pressing member 40 is provided with a critical length in relation to the overall length of the planar form 36, including the tab 38, so that it engages the full length of the rectangular portion 37, but only engages a part of the length of the tab 38. Pressing member 40 is provided with a sharp edge 41 at its end adjacent the tab 38. When the planar body 36 is placed between the mandrel 39 and the pressing member 40 and pressure is applied to the pressing member, a portion of the planar body as well as a portion of the tab is rounded as shown in Figure 11. The sharp edge 41 on the pressing member 40 performs two functions on engaging the tab 38. It serves to form a sharp transition area or step between the area of curvature imparted by the forming tool and the original planar form of the tab extending beyond the pressing member 40, and it also automatically results in a slight deflection of the flat uncurved end portion of the tab away from the surface of mandrel 39 due to a tensile

force resulting from the formation of the step referred to and applied to the top surface of the flat portion of the tab, having the effect of pulling said surface portion toward said step.

- 5 The under face of the flat planar portion of the tab serves to retard this pulling action, and the combination of this retarding action with the pulling action referred to results in a deflection laterally of the flattened portion of the tab from the mandrel 39. This slight deflection is usually sufficient to cause the free end of the tab to clear the end of an adjacent sleeve traveling on elongated mandrel 32, although not usually sufficient to cause the tab to clear the bead 30 on an adjacent sleeve.

It will be appreciated therefore that my novel method of forming a cathode sleeve with an integral tab results in an improved sleeve having a structure that contributes appreciably to ease in manufacture. Thus my novel method provides a cathode sleeve having a novel integral tab that has many advantageous characteristics. For example, the slight lateral deflection of the end portion of the tab contributes to ease in clearing the end portion of an adjacently disposed sleeve. Again, the flat end portion of the tab further contributes to facility in clearance between the tab on a sleeve and the bead on an adjacent sleeve. According to my invention therefore the desirable method of transporting cathode sleeves from a sleeve making machine to a receptacle by causing the sleeve to travel in tandem on the mandrel, in response to a pushing force, is permitted without the danger of buckling or collapse of the tab.

After the sleeve has been partly formed in accordance with the method of my invention it may be completed by conventional methods to bring the two edges thereof 42 and 43 into engagement in any suitable manner such as by way of a lock seam, not shown.

Another respect in which my novel cathode sleeve is advantageous is illustrated in Figure 12 which is a section along 12-12 of Figure 1 and which shows the improved connection to a lead-in that my novel tab permits.

Usually in order to make a connection between a cathode tab and a lead-in the two are disposed in transverse relationship. When this relationship is assumed in association with my novel tab, the flattened end portion of the tab affords a planar surface that is parallel to a longitudinal portion of a lead-in 26 as shown in Figure 12. This provides the maximum area of engagement between the lead-in and the tab, and a weld 34 therebetween constitutes a relatively large body for good mechanical and electrical connection. Figures 13 and 14 show deficient connections resulting from connecting a curved tab to a lead-in. 60 If the lead-in is connected to the outwardly curved side of the tab, the weld will connect only a relatively small surface of the tab to the lead-in. The side edge portions of the tab are more displaced from the lead-in than the central portion thereof with the result that the weld will include only the central portion of the tab. If the lead-in is connected to the inwardly curved side of the tab, edge portions thereof will be closer to the lead-in than the central portion thereof, resulting in a weld of the edge portions only of the lead-in to the tab.

This advantage of my invention insuring a good connection between a lead-in and a cathode tab results solely from the structure of my tab comprising a flattened end portion thereof,

and is entirely unrelated to the bead 30. As a consequence my invention may be practiced utilizing a cathode sleeve without the head 30.

Other advantages and embodiments of my invention will be readily apparent to persons skilled in the art. It is, therefore, desired that the invention be given a scope commensurate with the appended claims.

What I claim is:

1. A cathode sleeve having an integral tab, a portion of said tab adjacent said sleeve following the curvature of said sleeve in cross section, and another portion of said tab adjacent the free end of said tab having a larger radius of curvature than said first mentioned portion and being substantially flat.

2. A cathode sleeve having an integral tab, a portion of said tab adjacent said sleeve being curved in cross section, and another portion of said tab adjacent the free end of said tab being substantially rectangular in cross section, whereby said first-named portion has a greater curvature in cross section than the second-named portion.

3. A cathode sleeve having an integral tab, the free end of said tab terminating in an edge having substantially rectangular shape, a portion of said tab adjacent said sleeve having a cross section including two curved opposite sides.

4. A cathode sleeve having an integral tab, said tab including a portion adjacent said sleeve having a curved cross section, and another portion adjacent its free end having a rectangular cross section and angularly disposed with respect to the axis of said curved cross section.

5. A cathode sleeve comprising a tubular portion and an integral tab extending from one end of said tubular portion, said tab having a curved cross section adjacent said tubular portion, said tab adjacent the free end thereof being flat.

6. An electron discharge device including a

5 tubular cathode having an integral single thickness tab extending from one end thereof, said tab having a curved cross section adjacent said tubular portion, a portion adjacent the free end of said tab being flat, a lead-in for said device, said lead-in being connected to the last-named portion of said tab.

10 7. A cathode sleeve comprising a tubular portion and an integral tab extending from one end of said tubular portion, said tubular portion having an annular bead adjacent the other end thereof, said tab having a curved cross section adjacent said tubular portion, a portion of said tab adjacent the free end thereof being planar and deflected angularly with respect to the axis of said tubular portion.

15 8. A cathode sleeve having an integral tab, the free end portion of said tab lying in a single plane and being angularly disposed with respect to the axis of said sleeve and terminating in an edge having substantially rectangular shape.
